HENRY N. LYONS, OF DOVER, NEW JERSEY, ASSIGNOR TO DOHERTY RESEARCH COMPANY, OF NEW YORK, N. Y., A CORPORATION OF DELAWARE

PROCESS OF AND APPARATUS FOR DISTILLING OIL

Application filed April 17, 1923. Serial No. 632,598.

This invention relates to a process of and apparatus for distilling oil, and more particularly to a process and apparatus whereby oil is distilled in such a manner as to directly separate the various oil fractions therefrom without the necessity of repeated distillations.

In the ordinary distillation of oil, the crude or other oil to be distilled, is vaporized in a single still, various cuts being made at different temperatures to remove the various fractions thereof. The various fractions such as gasoline, kerosene, lubricating oils, etc., which are separately obtained are then redistilled to withdraw the lighter and heavier portions associated therewith from the desired fractions. The lighter portion distilled from each fraction is added to the next lighter fraction and the heavier portion therefrom is added to the next heavier fraction. For example, in distilling the kerosene fraction the more volatile portion is added to the gasoline fraction and the residue heavier than kerosene is added to the gas oil or next heavier fraction. In the same manner in the distillation of the gasoline, cut the heavier portion, which constitutes the higher boiling material, is separated from the gasoline and is added to the kerosene fraction. The various fractions after their distillation to remove undesired hydrocarbons therefrom are chemically treated to remove undesired impurities. In carrying out the various distillations a large amount of fuel is employed and a great deal of time is consumed for the various operations. Moreover, with the method generally employed for the separation of the various fractions from oil, a large layout of apparatus is necessary per unit of product obtained.

The primary object of the present invention is to provide a process and apparatus whereby oil may be distilled to obtain the desired final fractions in one distillation.

Another object of the invention is to provide a process and apparatus whereby the fuel consumption in the distillation of oil is substantially reduced.

50 A further object of the invention is to

fractionate vapors of different oil fractions in a fractionating tower so that the vapors of the heavier oil fractions do not come into contact with the vapors of lighter fractions during their condensation, thereby avoiding 55 solution of the lighter vapors in heavier condensed oil bodies which would require heat for their subsequent removal therefrom.

A further object of the invention is to 60 carry on the condensation of the various oil vapor fractions produced from the oil being distilled in such a manner that the lowest boiling or lightest portions of the vapors of each fraction will be passed into and mixed 65 with the vapors of the next lower boiling fraction undergoing condensation, while the highest boiling constituents condensed from each vapor fraction will be mixed with the vapors and condensate of the next higher 70 boiling fraction.

A further object of the invention is to provide a bubbling tower which is suitable for separating oil vapors to obtain liquid fractions of varying densities at different 75 vertical levels, having substantially uniform density at a given level therein.

A further object of the invention is to provide a bubbling tower in which vapors of varying densities may be supplied to the 80 tower at different levels corresponding substantially to the character of the liquids to be withdrawn at that level.

With these and other objects in view the invention consists in the process and apparatus for distilling oil hereinafter described and particularly defined in the claims.

The present invention is based upon the discovery that the various oil fractions 90 which it is desired to obtain may be separated from oil and the higher and lower boiling hydrocarbons may be removed from each fraction all in one operation. Instead of having a single still and distilling off 95 the various fractions therein the oil is passed through a series of stills continuously in such a manner that a series of vapor fractions are simultaneously obtained corresponding to the usual vapor cuts of gaso- 100

line, kerosene, and heavier oils. All of the vapors from the series of stills are passed directly into a single fractionating column wherein the vapor fractions remain separate except for the separation of the lighter and heavier constituents from each fraction which, with the exception of the gasoline portion, are added to the next lighter and next heavier fraction respectively.

10 The various oil fractions with the exception of the gasoline fraction are condensed in the column. The various fractions from the oil are therefore obtained directly without the necessity of repeated distillations and are then ready for the usual chemical process of purification.

15

The invention may be best explained in connection with the accompanying drawings, in which:

20 Fig. 1 is a view in elevation of a distilling apparatus embodying the preferred form of the invention;

Fig. 2 is a plan view of the apparatus shown in Fig. 1;

25 Fig. 3 is a vertical section of the fractionating or bubbling tower of the apparatus;

Fig. 4 is a sectional view taken on the line 4—4 of Fig. 3;

30 Fig. 5 is a sectional view taken on the line 5—5 of Fig. 3, and

Fig. 6 is a sectional view taken on the line 6—6 of Fig. 3.

Oil to be distilled is passed from storage or other source through a pipe 10 having a valve 12 therein into the first still 14 of a series of stills of the usual form of continuous stills which are heated by furnace gases or in any other desired manner. The stills are arranged preferably at 35 successively lower levels in the series to permit oil to flow by gravity through the series. A portion of the oil is distilled in the first still 14, the vapors thereof passing through a vapor drum 16 to a vapor pipe 18 which leads to a water cooled condenser or other condensing means in which the vapor fraction is condensed. The first vapor fraction obtained from the oil consists of gasoline or other light vapors, the composition of 40 which may be controlled by the rate of admission of oil and the rate of firing. It is desirable to maintain the temperature of the vapors from the still 14 at substantially 350° F. to obtain the proper vapor cut. If 45 desired, the oil passing to the still 14 may be preheated by passing the incoming oil through a series of heat interchangers 100, 110, 118 and 73 which will be further described in connection with the operation of 50 the apparatus. The oil which remains undistilled in the still 14 passes by means of pipe 20 having valves 22 and 24 therein to a still 26, in which the oil is heated to a higher temperature, preferably in the neighborhood of 400° F. In the still 26 a second

vapor fraction is withdrawn from the oil which passes through a vapor dome 28 to a pipe 30 and from thence into a fractionating tower 32. The oil remaining undistilled in the still 26 passes through a pipe 34, having valves 36 and 38 therein, to a still 40 similar to stills 14 and 26 in which the oil becomes still further heated to release another vapor fraction. Vapors which are evolved in the still 40 pass through a dome 42 to a pipe 44 leading to the fractionating tower 32 at a point considerably below the point at which pipe 30 is connected therewith. The vapors passing through the pipe 44 are at a temperature considerably higher than those passing through the pipe 30, the firing of the still being regulated so that a vapor temperature of substantially 450° F. may be maintained. The oil which remains unvaporized in the still 40 passes through a pipe 46 having valves 48 and 50 therein to a still 52, in which the oil becomes further heated and the vapors liberated therefrom attain a temperature of substantially 500° F. The vapors which are released from the oil in the still 52 pass upwardly through a dome 54 on the still to a pipe 56 which leads to the fractionating tower 32 at a point below that of the connection of pipe 44 therewith. The residual oil which remains unvaporized in the still 52 passes through a pipe 58 having valves 60 and 62 therein to a still 64 in which the last vapor fraction to be taken from the oil is removed and conducted upwardly through a dome 66 to a pipe 68 leading to fractionating tower 32 at the bottom thereof. The vapors in the still 64 attain ordinarily a temperature in the neighborhood of 550° F. but the temperature may vary widely with different oils. The portion of the oil remaining undistilled in still 64 passes through an exit pipe 70 having a valve 72 therein, and may be then passed through heat interchanger 73 for preheating oil advancing to the still 14.

The fractionating tower 32 makes use of the reboiling features of the ordinary bubbling type tower but is constructed in a manner such that a new principle of operation is involved in the fractional distillation of vapors. The tower is made up of a number of sections corresponding to the number of stills in the series of stills from which vapors are passed to the fractionating tower. The lowest boiling point vapors to be passed to the tower are conducted from the still 26 through the pipe 30 to the lower portion of the upper section or "gasoline section" of the tower. In each of the sections there are a series of plates 82 (Fig. 3) which have a series of pipes 84 extending upwardly to permit vapors to pass through the plates. Over the top of the upwardly extending 125

pipes 84 are bubbling caps 86, by means of which vapors passing through the pipes are forced to pass beneath the surface of liquid on the plates during the passage of the 5 vapors upwardly through the tower. Extending through each plate is an overflow pipe 88 through which liquid passes downwardly through the tower from one plate to the next. At the top of the tower is a 10 cooling coil 90 which is supplied with water or other cooling liquid for the purpose of condensing out higher boiling vapor constituents to accurately control the boiling point of the vapor fraction passing from 15 the top section of the tower. The uncondensed gases and vapors which leave the top of the tower 32 pass through an outlet pipe 91 to a condenser 92 where the condensable vapors are recovered. The condensate recovered in the condenser 92 consists of high gravity high test gasoline 20 which may be blended with other gasoline to make motor fuel.

The vapors passing through the upper or 25 "gasoline section" consist of the vapors which are introduced through the inlet pipe 30, and the vapors passing through the plate 32 immediately below the discharge end of pipe 30 at the bottom of the "gasoline section." A coil 93 is placed in the bottom compartment of the "gasoline section" in which may be circulated water, oil, or any desirable cooling medium to condense the higher 30 boiling point portions in the vapors and permit only the lower boiling point vapors to pass into the second compartment of the "gasoline section." As the vapors pass up 35 through the gasoline section they pass through a series of bodies of liquid condensates which have progressively lower 40 boiling points. These bodies are constantly boiled and reboiled or evaporated and recon- densed by means of the latent heat in the vapors, and the boiling points of the bodies 45 of liquid in each compartment become substantially constant and vary only slightly in the degree of their boiling points. The higher boiling point liquids work down through the compartments so that the highest 50 boiling fraction is at the bottom. The fraction reaching the bottom of the "gasoline section" is a gasoline product having a comparatively high end point which is suitable for blending with other lower boiling 55 point gasoline to form a motor fuel. This heavy gasoline or low end point naphtha may be drawn through an outlet pipe 94, and passed through a valve 96 and trap 98, and conducted to a heat interchanger 100, by 60 which it may be cooled and at the same time used to preheat the fresh oil advancing to the still 14. The cooled condensate passing through the interchanger 100 will then be conducted to suitable storage. By use of 65 the refluxing coil 93 the boiling point of the

oil in the bottom compartment of the "gasoline section" may be accurately controlled. To assist the control of the boiling point of the gasoline and the withdrawal through the trap 98, a valve 101 is placed in the overflow pipe 102, leading from the bottom plate of the "gasoline section" into the upper compartment of the "kerosene section."

Vapors from the still 40 in which the vapor fraction corresponding to kerosene is 70 distilled from the oil, pass through the vapor dome 42 into the pipe 44, and from thence into the lower portion of the second or "kerosene section" of the tower which has substantially the same construction as the 75 first or upper section. The vapors pass upwardly through the plates in this section and encounter the portion of the condensate from the first section which passes through the overflow pipe 102 having valve 101 there- 80 in, and downwardly through the plates of the second section. In the lowest compartment of the second section and adjacent the inlet pipe 44 is a coil 103 similar to coils 85 90 and 93, by which vapors from the third section are cooled to condense a portion of the vapors at this point. The material which is condensed in the second or kero- 95 sene section is drawn off at the bottom plate of the compartment immediately below the discharge end of vapor inlet pipe 44, by means of a pipe 104, having a valve 106 and a liquid trap 108 therein. The liquid which is withdrawn through pipe 104 passes downwardly into the heat exchanger 110 from 100 which it may be passed to a receiver or utilized as desired.

Vapors from the still 52, in which the next higher boiling point fraction is distilled, 105 pass upwardly through a pipe 56 into the tower in the lower portion of a third or "gas oil" section in which the vapors heavier than kerosene are condensed. The vapors passed into the third section travel upwardly through the plates and are condensed in 110 the same manner as has previously been de- scribed in connection with the first and sec- 115 ond sections. In the lowest compartment of the third section is a coil 111, similar to coils 90 and 93, which is placed in prox- 120 imity to the incoming vapor pipe 56 leading to the section. The condensed portion of the vapors together with a small portion of the heavier liquids from the section above pass downwardly from one plate to the next 125 in the "gas oil" section and finally pass to the compartment immediately below the vapor outlet end of pipe 56, from which the condensates are withdrawn through a pipe 112, which is provided with a valve 114 and 130 a liquid trap 116. From the pipe 112 the liquid passes into a heat exchanger 118 to be cooled and passes from thence to storage.

Vapors from the last still 64 in the series 135 pass by means of the pipe 68 to the bottom

of the tower into the lowest or fuel oil section thereof, in which the heaviest vapors are condensed. The vapors pass upwardly through the plates and are finally condensed or pass into the section above to unite with the lighter vapors therein. The condensed portion of the vapors passes downwardly from plate to plate through the overflow pipes of the section and is finally withdrawn from the tower by means of the pipe 120, having a valve 122 therein. The pipe 120 is connected to the last still in the series so that the portion condensed in the lowest section of the tower may be redistilled to remove the lighter fractions thereof. If it is found to be desirable with a particular oil the pipe 120 may be connected directly to a heat interchanger and from thence to a storage receptacle instead of being redistilled as above described. The still bottoms are continuously withdrawn from still 64 through outlet 70 and heat interchanger 73.

The oil which is to be treated in the apparatus above described is preferably pre-heated by passing the oil through the heat exchangers 100, 110, 118 and 73 in heat exchange with distillates from the tower 32 and residue from the still 64. It is apparent that the distillates from the higher parts of the fractionating tower are at the lowest temperatures, and it is evident therefore to one skilled in the art that the oil to be pre-heated should be passed first through the heat exchangers at the lower temperatures. It is preferred therefore to pass the oil first through the heat exchanger 100, through which condensate from the gasoline section is passed, and next through the heat exchanger 110, through which condensate from the kerosene section is passed, then through the exchanger 118, through which condensate from the third section or heavy distillate section is passed and finally through the residuum heat interchanger 73. The course of the oil to be preheated by passing through said preheaters is indicated by arrows having a short line crossing the same, the inlet pipe leading from storage to the first heat exchanger 100 being indicated by numeral 11 and the pipe leading from the last heat exchanger 73 to the still 14 being indicated by numeral 13.

With the construction outlined above two different types of distillation are brought into combination. The first type involves the use of a set of five continuously operated fire stills in which a primary distillation is effected. In each of the five stills a separate vapor product is removed and each of these products is introduced at different levels into a fractionating column still of the bubbling type. In the bubbling type column still a rectification of the vapors is carried on by which a large number of different condensates are produced and from which dis-

tinct fractions may be removed to recover a series of fractions from the oil. This combined form of distillation differs widely from the ordinary type of distillation commonly used for distilling binary mixtures such as alcohol and water and acetone and water, in which a primary distillation or boiling or evaporation is carried out in a cylindrical still and the vapors passed up through one tall column. A fractionating column has been used to some extent for petroleum distillation but petroleum is not a binary mixture, on the contrary it is comprised of such a large number of different hydrocarbons that it has been necessary to use a large number of trays in a column still. Such a large column still, that is, containing from 30 to 45 trays or compartments, is very expensive and does not have a large capacity. In the place of having a large column still for each one of the continuous primary stills, applicant has obtained the same effect by one column still. This column still is divided into sections and carries on the same type of concentration as would be carried out in the ordinary type of column still. In the applicant's process, however, the concentrated distillates do not flow back to the primary still, but portions thereof are withdrawn while other portions remain in the column to aid in the rectification of the vapors conducted from the primary stills. By this means applicant gains the advantage of heat necessary for distillation in that the only heat supplied is the latent heat of evaporation or condensation of the vapors, and no sensible heat is supplied such as would be supplied if the condensates were returned to the primary stills. Furthermore, when condensates go back to a primary still containing petroleum, the selective separation of condensates into bodies having specific boiling points is lost because these fractions are immediately blended with the petroleum of the still, and therefore the effect or work of the column still is entirely lost. In the applicant's case, however, the boiling points of the various fractions are maintained substantially constant throughout the entire column still and the vapors from the various primary stills pass through the fractions having boiling points very close to the boiling point of the particular vapors. Furthermore, while obtaining the effect of a high column still applicant's column still has an increased capacity because the light or lower boiling point vapors are introduced into the column still in the section in which the condensates have similar boiling points and therefore it is not necessary to tax the capacity of the still by putting the low boiling point vapors into the bottom of the still and requiring them to pass entirely through the column and thus scrubbing these low boiling point

Vapors with a large number of condensate bodies of much higher temperature and boiling point.

In the claims the phrase "distilling column of the bubbling type" has been used to define the type of distillation carried on in the bubbling tower 32. By this clause it is intended to cover all forms of rectifying stills or towers in which the vapors introduced thereto or formed therein are caused to pass in contact with a series of bodies of condensate of successively lower temperature and average boiling point, in each body of which portions of said vapors are condensed and portions of the condensate of the body are vaporized. It is not necessary that such columns have bubbling caps because many forms of bubbling type or reboiling columns are in common use.

It is contemplated that various modifications may be made in the process and apparatus of the present invention without departing from the spirit or the scope of the invention as described. It is to be understood that the temperatures of the vapors in the stills in the series will vary with the character of the oil treated and that the applicant does not limit his invention to the temperatures as set forth.

Having thus set forth the invention, what is claimed as new is:

1. In an oil distillation apparatus, a series of stills, means for passing oil continuously in series through the stills, a fractionating column containing a plurality of condensing means, means for passing vapors having substantially different boiling points from each still to the column at different points corresponding to the temperature of the vapors from each still, means in the column for drawing off condensate therefrom at different heights and means for collecting the condensates therefrom.

2. In an oil distillation apparatus, a plurality of stills, means connecting the stills in series to withdraw oil from one still and pass it to the next in the series, a fractionating column, a vapor connection between each of the stills and the fractionating column, said vapor connections leading into said column at different points, whereby vapors of substantially different boiling points may be introduced into said column at a level corresponding to the relative boiling temperature of the vapor from each of said stills, means for introducing oil into the first still in the series and means for withdrawing oil from the last still in the series.

3. In an oil distillation apparatus, a plurality of stills, means connecting the stills in series to pass oil from one still to another in series, a fractionating column, means connecting the vapor space of each still with the fractionating column, the points of connec-

tion between the stills and the column being at different levels on the column corresponding to the boiling temperature of the vapors conducted from each still, a plurality of heat interchangers, means connecting the said column with the said heat interchangers to pass condensed vapor portions from the column to the interchangers, means for passing oil to be distilled through the series of heat interchangers to the still first in the series and means for withdrawing residual oil from the still last in the series.

4. In an oil distillation apparatus, a plurality of stills adapted to be maintained at progressively increasing temperatures, means connecting the stills in series permitting the passage of oil from one still to the next in the series, means for passing oil to the first still in the series, means for withdrawing residual oil from the last still in the series, a fractionating column having vapor inlets and condensate outlets at different vertical levels in the column, means for conducting vapors from the first still of the series to the uppermost vapor inlet in said column, and means for conducting vapors from each successive still to a successively lower vapor inlet in said column whereby said vapors are introduced into said column at different levels corresponding to the respective boiling temperatures of the vapors from each of said stills.

5. In an oil distillation apparatus, a plurality of stills adapted to be maintained at progressively increasing temperatures, vapor outlets in the stills, means for heating the said stills, means connecting the stills to permit the passage of oil in series through the stills, a series of heat interchangers, means for passing oil through the heat interchangers to the still first in the series, means for withdrawing residual oil from the still last in the series, a fractionating column having vapor inlets at different vertical levels therein, condensate outlets at vertical levels different from that of the vapor inlets, means connecting the vapor outlets of the stills first in the series with the vapor inlets of the column at the highest levels, whereby the vapors of different average boiling point are introduced into said column at different levels corresponding to the respective boiling temperatures of the vapors from each of said stills, and means for conducting condensate from the condensate outlets in the column to the heat interchangers.

6. A process of distilling oil comprising passing oil through a series of vaporizing zones, withdrawing a series of vapor fractions of different boiling point from said zones, passing vapors from the first zone into a condensing zone, passing the vapors from the remaining vaporizing zones into different levels of an independent vapor

- separating and condensing zone to condense vapors at different levels corresponding to the relative boiling temperature of each vapor fraction, withdrawing condensed vapors at different levels and passing the uncondensed vapors into a final condensing zone.
7. A process of distilling oil, comprising passing oil through a series of vaporizing zones, withdrawing a series of vapor fractions of different boiling point from said zones, passing vapors from the first zone into a separate condensing zone, passing the vapors from the remaining zones in the series into different levels of a vapor separating and condensing zone whereby the vapors of different boiling points are introduced into the said vapor separating and condensing zone at levels corresponding to the boiling temperature of the said vapors, the lighter vapors passing to the higher levels therein, condensing vapors in the separating and condensing zone, withdrawing condensate at different levels of the said separating and condensing zone, withdrawing the uncondensed vapor portion from the separating and condensing zone and separately condensing the condensable portion thereof.
8. A process of fractional distillation which comprises distilling oil in a series of bodies to separate a series of vapor fractions having different boiling points, separately introducing the vapor fractions into a distilling column of the bubbling type at different levels thereof to effect a further fractionation of said vapors, and simultaneously withdrawing a series of fractional condensates of different boiling points from different levels of the column.
9. A process of fractional distillation which comprises distilling oil in a series of bodies to separate a series of vapor fractions having different boiling points, separately introducing the vapor fractions into a distilling column of the bubbling type at different levels to effect a further fractionation thereof and simultaneously withdrawing a condensate from the column adjacent the point of admission of each vapor fraction.
10. A process of fractional distillation which comprises distilling oil in a series of bodies to separate a series of vapor fractions having different boiling points, separately introducing the vapor fractions into a distilling column of the bubbling type at different levels, introducing a cooling medium into different levels of the column to reflux the vapors and simultaneously withdrawing a series of fractional condensates of different boiling points from the column.
11. A process of fractional distillation which comprises advancing oil through a series of stills in succession, progressively raising the temperature of the oil as it advances to separate a vapor fraction of different boiling point in each still, and separately introducing the vapor fractions into different portions of a column still of the bubbling type to effect a further fractionation thereof.
12. A process of fractional distillation which comprises advancing oil through a series of stills in succession, progressively raising the temperature of the oil as it advances to separate a vapor fraction in each still, the boiling point of the respective fractions increasing in the direction of the advance of the oil and separately introducing the vapor fractions into a column still of the bubbling type at different levels, the boiling points of the fractions decreasing from the bottom to the top of the column.
13. A process of fractional distillation which comprises advancing oil through a series of stills in succession, progressively raising the temperature of the oil as it advances to separate vapor fractions of progressively higher boiling points, separately introducing the vapor fractions into different portions of a column still of the bubbling type to effect a further fractionation thereof and separately and simultaneously removing fractional condensates from different levels of the column.
14. A process of fractional distillation which comprises advancing oil through a series of stills in succession, progressively raising the temperature of the oil as it advances to separate a vapor fraction in each still, separately introducing the vapor fractions into different portions of a column still of the bubbling type, separately removing fractional condensates from different levels of the column and introducing a cooling medium into the column to reflux vapors adjacent the points of removal of the condensates.
15. A process of fractionally distilling oil, which comprises continuously advancing crude oil through a series of stills maintained at progressively higher temperatures in the direction of flow of the oil whereby a series of vapor fractions having different boiling points are simultaneously produced, introducing the said vapors into a common rectifying column at different levels corresponding to the relative boiling temperature of each fraction, the lower boiling vapors being introduced into the column at the highest level, subjecting each vapor fraction to rectification in said column in a restricted zone, withdrawing a condensate from each zone and passing vapors remaining uncondensed in each zone into the zone next above.
16. A fractionating condenser having separate inlet openings for vapors of different boiling points at points in said condenser

at which different temperatures are maintained.

17. The method of fractionally condensing a plurality of vapor streams, each of 5 different average boiling point, which comprises introducing said vapor streams simultaneously into a single condenser stream at intervals therealong, said single stream being maintained at progressively lower temperatures from the first inlet to the outlet opening.

18. The method of fractionally condensing a plurality of vapor streams, each of different average boiling point, which comprises introducing said vapor streams simultaneously into a single vapor stream maintained at progressively lower temperatures from one end to the other at points having temperatures substantially proportional to 10 the average boiling point of each vapor stream.

19. In an oil distilling apparatus, a plurality of stills arranged in series, means for conducting oil through the stills in series, 25 means for heating the stills to progressively higher temperatures in the direction of flow of oil therethrough whereby a series of vapor fractions having different boiling points are simultaneously produced, a vapor fractionating column, means for conducting vapors from the first still of the series and introducing them into the upper portion of said column, means for conducting vapors from each succeeding still of the series and 30 for introducing them into said column at successively lower levels whereby said vapors are introduced into said column at different levels corresponding to the boiling temperature of each fraction.

20. The process of condensing a plurality of vapor streams of different boiling point, which comprises introducing the said vapor streams simultaneously and separately into a vapor fractionating zone in which progressively decreasing temperatures are maintained in the direction of flow of vapors therethrough, the lower boiling point vapors being introduced into a portion of said zone in which the temperature is relatively low 45 and the higher boiling point vapors being introduced into the highest temperature portion of said zone, and substantially separately rectifying the vapors of each stream in said zone.

21. A process of fractionally distilling oil, which comprises continuously advancing crude oil through a series of stills maintained at progressively higher temperatures in the direction of flow of the oil, whereby 50 a series of vapor fractions having different boiling points are simultaneously produced, introducing the said vapors into a common rectifying column at different levels corresponding to the relative boiling temperature 55 of each fraction, the lower boiling vapors

being introduced into the column at the highest level, subjecting each vapor fraction to rectification in said column in a restricted zone, withdrawing a condensate from each zone, and refluxing higher boiling condensate produced in each zone into the zone next below.

In testimony whereof I affix my signature.
